UNITED STATES PATENT OFFICE.

GEORGE H. ULLMAN, OF NEW YORK, N. Y., ASSIGNOR TO L. PLAUT & CO., OF NEW YORK, N. Y., A COPARTNERSHIP.

DESIGN FOR A PLAQUE FOR LIGHTING-FIXTURES.

No. 40,164.

Specification for Design.

Patented July 20, 1909.

Application filed March 30, 1909. Serial No. 486,831. Term of patent 7 years.

To all whom it may concern:

Be it known that I, GEORGE H. ULLMAN, a citizen of the United States, and a resident of the borough of Manhattan, city, county, and State of New York, have invented a new, original, and ornamental Design for a Plaque for Lighting-Fixtures, of which the following is a specification, reference being had to the accompanying drawing, forming a part hereof, which shows a plan view of the design.

The design comprises a plaque of substantially circular shape, having on the outer part a representation of a plurality of grotesque heads with open mouths and foliated

beards. Between the heads are representations of ornate fleurs de lis. Depending from the cheeks of the heads are representations of serpents which extend toward the center of the plaque and are intertwined. At the center of the plaque is an arrangement representing leaves and fruit surrounding a rosette.

I claim:

The ornamental design for plaque for lighting fixture, as shown and described.

GEORGE H. ULLMAN.
